UNITED STATES PATENT OFFICE.

BERNHARD HESS, OF FOREST PARK, ILLINOIS.

PROTECTOR FOR ENGINE HOODS.

Application filed February 9, 1920, Serial No. 357,832. Renewed December 15, 1922.

To all whom it may concern:

Be it known that I, BERNHARD HESS, a citizen of the United States, residing at Forest Park, in the county of Cook and 5 State of Illinois, have invented new and useful Improvements in Protectors for Engine Hoods; of which the following is a specification.

This invention relates to improvements in 10 protectors for engine hoods.

The hoods of automobile engines frequently are provided at their sides with openings for the admission of air into the interior of the hood, this admission of air 15 in a predetermined direction being facilitated by flanges projecting outwardly and partly overlapping the openings in the hood.

An object of the present invention is to 20 provide a protector which can readily be attached to an engine hood for closing these openings to prevent the admission of air therethrough, and to prevent thereby a freezing of the cooling fluid which during 25 the operation of the engine is circulated through a jacket of the engine.

It is also an object of the invention to 30 provide a readily removable clamp for securing a protector plate of this character to the walls of the hood, and to render this 35 clamp as little conspicuous as possible so as not to detract from the characteristic appearance of the respective engine hood.

It is also an object of the invention to 40 provide a clamp and protector of this character which can readily be secured to the wall of the engine hood without interfering, after its attachment, with the opening of this wall.

With these and other objects in view an embodiment of the invention is illustrated in the accompanying drawing and described in the following specification.

In the drawing:

Fig. 1 shows an engine hood in side elevation, with the protector plate secured to the inner surface of the wall;

Fig. 2 is, on an enlarged scale, a horizontal section through this wall and protector plate, and

Fig. 3 shows perspectively a portion of the protector plate and clamp.

The side wall 1 of the hood is provided with a plurality of slots 2, over which project louver portions 3, which are spaced from the plane of the wall at their free

edges, but which merge into said wall at their outer edge. They permit the admission of air through the slots 2 in a predetermined direction.

In order to prevent the admission of air through the slots 2 in extremely cold weather, a protector plate 4, made of suitable sheet material, as metal, card board, wood or fiber, is detachably secured to the inner surface of the wall. The attachment is effected in the present embodiment by means of clamps which are held to the wall 1 through the slots 2 thereof.

The clamps 5, in the present embodiment, 70 are made of a single piece of wire or the like adapted to hold the protector plate detachably against the inner surface of the hood, owing to the resiliency of the material of which they are made. The clamps comprise rubber covered holding portions 6, 75 bent at approximately right angles from hood and plate traversing portions 7, from which angular arms 8 project oppositely in vertical direction. The angle which the 80 arms 8 normally form with the hood traversing portions 7 is somewhat more acute than shown, so that in the application of these clamps a slight deformation of these angles occurs. Although the inner portions 85 of these arms 8 are spaced from the protector plate, the outer portions of the same are forced to rest against the protector plate, and as the clamping portion 6 is held in engagement with the outer surface of the 90 hood it is obvious that the outer ends of the arms will force the protector plate into engagement with the inner surface of the wall.

For the purpose of increasing the leverage with which the arms act on the protector 95 plate, the point of engagement of said arms with the protector plate is at a relatively large distance from the slots 9, through which the traversing portions 7 of the clamp pass through the protector plate. This frictional engagement of the outer ends of the arms with the outer portions of the protector plate is furthermore enhanced by the formation of longitudinal arms 10 bent at approximately right angles to the first mentioned arms 8 and lying in engagement with the protector plate.

When it is desired to attach a plate to the inner wall of the hood the clamp is passed through the longitudinal slot 9 of the plate 110 and brought into engagement with a portion of the wall of the hood on the outside there-

of. This will then firmly hold the outer ends of the arms in engagement with the protector plate; and, owing to the resiliency of the material, this engagement will be maintained until the clamping portions on the outside are again shifted into a position in which they can be withdrawn automatically through the slots in the outer wall and through the longitudinal slots in the inner wall of the plate. The length of the slots permits of suitable adjustment of the plate with respect to the wall.

I claim:

1. In combination with the wall of an engine hood having perforations, a protector plate secured to the inner surface of said wall and covering said perforations, and detachable clamps extending through said perforations and removably holding said plate to said wall.

2. In combination with a wall of an engine hood, a protector plate, the wall of the hood being provided with openings, and the protector plate being adapted to cover said openings, and a one-piece clamp extending through one of the openings of the engine hood and engaging the outer side of said engine hood and the inner side of said plate.

3. In combination with the wall of an engine hood having perforations, a plate secured to said wall and covering said perforations, and a one-piece clamp having a portion engaging the outside of the engine hood and other portions engaging the inner side of the protector plate, said last named portions being forced into engagement with the protector plate through the resiliency of the material of which the clamp is made.

4. A one-piece clamp for protector plates

of engine hoods comprising a wall-engaging portion, a wall-traversing portion, and arms extending from said wall-traversing portion in opposite directions into engagement with said plate.

5. A one-piece clamp for fastening protector plates to engine hoods, said engine hoods being provided with openings, the clamp consisting of a wall-engaging portion, a wall-traversing portion, bent at approximately right angles to said first named portion, and plate engaging arms extending from said traversing portion in opposite directions into engagement with said plate.

6. A one-piece clamp for securing protector plates to the walls of engine hoods, said walls being provided with perforations, said clamp consisting of a wall-engaging portion, a wall-traversing portion extending through a perforation, arms extending from said last named portion angularly into engagement with said plate, and fingers projecting angularly from said arms in engagement with said plate.

7. In a device of the character described, a plate having an opening and a clamp having one portion engageable with the part to which the plate is to be secured, and another portion projecting through an opening in the plate, and arms extending from said last named portion to a point remote from said opening.

In testimony whereof, I have affixed my signature, in the presence of two witnesses:

BERNHARD HESS.
